EVAPORATIVE COOLING SYSTEM FOR
INTERNAL-COMBUSTION ENGINESArthur W. Pope, Jr., Waukesha, Wis., assignor to
Waukesha Motor Company, Waukesha, Wis.

Application June 8, 1950, Serial No. 166,893

12 Claims. (Cl. 123—41.23)

1

This invention relates to cooling systems for internal combustion engines, and more particularly to evaporative type systems wherein coolant is caused to circulate by both thermal siphon action and by the energy of steam discharging from the engine cylinder water jacket.

It is an object of this invention to provide an improved evaporative type cooling system wherein steam generated in the engine cylinder jacket flows through a duct wherein is established a region of high velocity, and a region of pressure reduced beneath the normal operating pressure of the system. A circulatory path is provided from the outlet of said duct through steam condensing and condensate cooling apparatus to the reduced pressure region of the duct whereby steam and water vapor issuing from the water jacket are condensed and cooled during flow through the circulatory path resulting from both thermal siphon action and the suction or negative pressure created in the duct.

Another object of the invention is to provide an improved evaporative type cooling system wherein coolant is delivered to the engine cylinder water jacket by the impact force of intermixed water and steam flowing at high velocity through a restricted passage.

Another object of the invention is to provide an improved evaporative type cooling system wherein the coolant is delivered to the engine cylinder water jacket in proportion to the velocity of the steam discharged therefrom whereby substantially constant temperature conditions are maintained during operation of the engine under various load conditions.

Another object of the invention is to provide an improved evaporative type cooling system wherein a Venturi jet circulator is employed for increasing the velocity of the stream flow and producing a region of reduced pressure to enhance the flow of the coolant both through a condenser-cooling flow circuit and through a flow path comprising the engine cylinder water jacket.

Another object of the invention is to provide an improved evaporative cooling system utilizing a Venturi jet circulating device formed by an annular member adapted to be inserted within a steam duct, said device having an interior wall provided with peripherally arranged apertures from which said wall diverges to form a flow passage through the member.

Another object of the invention is to provide an improved evaporative type of cooling system wherein air entrapped in the feed line to the engine cylinder water jacket is vented into the circulatory cooling system.

2

A further object of the invention is to provide an improved evaporative type cooling system which functions in an efficient manner without the use of pumps, check valves, or other accessories having movable parts, and which permits the radiator to be placed in a conventional vertical position adjacent to an internal combustion engine.

A still further object of the invention is to provide an improved evaporative type cooling system wherein reserve cooling capacity is provided to absorb the residual heat of the engine after operation has been terminated, thereby eliminating the blowing off of steam and the loss of coolant from the system.

The invention also resides in certain novel structural characteristics which facilitate the carrying out of the foregoing objects and which contribute both the efficiency of the improved evaporative type cooling system and to its simplicity of construction as well as to the dependability of its operation.

Other objects and advantages of the invention will become apparent from the following detailed description taken in connection with the accompanying drawings, in which:

Figure 1 is a view partly in elevation and partly in section showing an internal combustion engine provided with the improved evaporative cooling system;

Figure 2 is a cross sectional view taken on line 2—2 of Figure 3 disclosing an alternative construction from the discharge passage through which steam flows from the engine cylinder water jacket; and

Figure 3 is a cross sectional view taken on line 3—3 of Figure 2.

While the invention is susceptible of various modifications and alternative constructions, I have shown in the drawings and will herein describe in detail the preferred embodiments. It is to be understood, however, that I do not intend to limit the invention to such disclosure for I aim to cover all modifications and alternative constructions falling within the spirit and scope of the invention as defined in the appended claims.

Referring to Figure 1 of the drawings, reference numeral 10 represents a cylinder block of an internal combustion engine identified by reference numeral 12. The cylinder block 10 is provided with a plurality of cylinders indicated generally by reference numeral 14 about which a cylinder water jacket 16 is positioned in a conventional manner. An outlet 18 is provided in the upper portion of the engine cylinder water jacket

16 through which steam and water vapor generated within the water jacket is discharged in a generally upward direction. A duct 20 having the inlet thereof in communication with the outlet of the water jacket is disposed in a vertical direction directly above the water jacket and serves as a conduit through which flow the steam and water vapor issuing from the water jacket. An orifice 22 is located in the wall of duct 20 intermediate the inlet and the outlet thereof having a connection thereto which is connected in the circulatory path of the coolant in a manner which will be hereinafter more fully described.

A steam condenser tank 24 is positioned immediately above the duct 20 with the steam inlet 26 which is located in the lower portion thereof, in communication with the outlet of the duct. The condenser tank 24 is provided with an outlet 28 located in the upper portion of the condenser chamber which serves as an egress for the coolant during the operation of the cooling system.

A radiator indicated generally by reference numeral 30 is provided in the system and is positioned adjacent to the engine in a conventional manner so that a fan or other air impelling device 32 may be conveniently positioned to create a flow of cooling medium through the air passages of the core 34 and across the adjacently positioned surfaces of the cylinder block 10 and water jacket 16 of the internal combustion engine 12. The radiator 30 is provided with an upper header 36 and a lower header 38 between which the core 34 is positioned. The upper header 36 is provided with an inlet 40 which is connected by a pipe or other conduit 42 with the outlet 28 of the condenser tank 24. The lower header 38 is provided with an outlet 44 which is connected by a condensate return pipe or other conduit 46 to the orifice 22 located in the wall of duct 20.

The engine cylinder water jacket 16 is provided with an inlet 48 positioned in the lower portion of the jacket and a feed line 50 is connected thereto through which coolant is supplied to the interior of the water jacket. The coolant is supplied to feed line 50 from a ram tube identified by reference numeral 52. The ram tube comprises a vertically extending tube section 54 having the inlet 56 thereof extending within the outlet of duct 20 and directed toward the path of steam issuing from outlet 18 of water jacket 16. The tube section 54 communicates with feed line 50 so that a portion of the coolant flowing through duct 20 is conveyed to the water jacket 16 by the impact pressure of the steam and coolant. A venting orifice 58 is positioned in ram tube 52 so that gases entrapped within the ram tube during the filling of the system may be vented into the interior of condenser tank 24.

The upper header 36 of the radiator 30 is provided with a filler opening 60 by which water or other liquid coolant may be introduced into the system. The filler opening is covered by a closure cap 62 which is provided with a venting orifice 64. The filler opening 60 is provided with a valve 66 which is normally biased to close the filler opening by compressing spring 68 when closure cap 62 is secured in position by cooperating threads 65 located on the header and closure cap.

The normal cold water level of the coolant in the system just described is indicated by line A—A, and lies just below the level of the bottom of pipe 42 which connects the chamber of condenser tank 24 with the upper header 36 of the radiator. The remaining interior portions of the

system, including the engine cylinder water jacket 16, duct 20, feed line 50, condensate return pipe 46, and substantially all of core 34 of the radiator 30, are normally filled with water. Due to the fact that the pipe connection 42 between the chamber of condenser tank 24 and the upper header 36 of the radiator is unfilled, no circulation of the coolant occurs until the water in the engine cylinder jacket reaches the boiling point, at which time the formation of steam bubbles in the engine cylinder jacket which rise through duct 20 displaces sufficient water in the cylinder jacket to raise the water level above the bottom of the pipe 42 which establishes a continuous flow path for the liquid coolant. The coolant at an elevated temperature will then flow from the condenser tank 24 through pipe 42 to the upper header 36 and pass through the radiator core 34 to the lower header 38. The liquid as it is cooled in this heat exchange device will descend to lower header 38 and will flow through the outlet 44 thereof into the condensate return pipe 46 and through orifice 22 into duct 20. As the boiling of the water in the engine cylinder jacket 16 increases with increase of engine load, the velocity of the steam flowing through duct 20 will increase and will cause a reduction of the pressure below the normal ambient pressure of the system by aspirator action within the duct in the vicinity of orifice 22. The lowering of the pressure in the region of orifice 22 produces in effect a suction or negative pressure which causes the ambient or normal pressure of the system to force condensate from the radiator through condensate return pipe 46 and orifice 22 into duct 20 where it will intermix with the steam issuing from outlet 18 of the engine cylinder jacket. Intermixing of the cooled condensate and steam results in the condensation of the steam with the liberation of heat whereby the temperature of the liquid coolant is increased.

As the hot coolant flows through the aforescribed circulatory path from condenser tank 24, through pipe 42 and through core 34 of radiator 30, it is cooled and its density is thereby increased. The coolant thereupon flows downwardly due to its increased density into lower header 38 and through condensate return pipe 46 and orifice 22 into duct 20. Thus the flow of coolant to duct 20 is aided by the thermal siphoning effect which results from the cooling of the liquid in the system in addition to the aspirator action created by the steam flow in duct 20 by virtue of which a negative pressure is created therein to induce the flow of coolant.

Coolant supplied from a zone in duct 20 in which condensate and steam are intermixed, is circulated to the lower portion of engine jacket 16 through feed line 50. The flow of coolant through feed line 50 is effected by the impact pressure of the steam and condensate flow within opening 56 of tube section 54 of ram tube 52. The magnitude of the impact pressure is dependent upon the velocity of the steam flowing through outlet 18 and is sufficient to force coolant into the inlet of the ram tube, through feed line 50 into the lower portion of engine cylinder jacket 16 to maintain the jacket filled with coolant during all conditions of engine operation.

Air which may be entrapped within vertically positioned tube section 54 of the ram tube during the filling of the cooling system is released through the venting orifice 58 to the interior of condenser tank 24 during filling of the cool-

ing system. The venting orifice 58 is formed with a small opening relative to the inlet of the ram tube so that leakage through the venting orifice does not adversely affect the operation of the system in forcing coolant to the engine water jacket.

The ambient pressure acting upon the surface of the liquid within the cooling system is preferably maintained slightly above the value of atmospheric pressure. Spring pressed valve 66 serves to maintain the filling opening 60 closed and to provide the increased pressure on the coolant within the system. The provision of operating the system under a pressure slightly above atmospheric pressure serves to prevent breathing of the system and eliminates the loss of coolant in the form of water vapor and steam from the system.

It may be advantageous in the cooling systems of certain types of internal combustion engines to increase the velocity of steam flow issuing through duct 20 and thereby obtain a relative greater negative pressure in the reduced pressure region of the connection between the engine cylinder jacket and the condenser chamber. Additionally, the increased velocity will provide a greater impact pressure at the inlet of the ram tube and thus increase the flow of coolant to the engine water jacket. My invention contemplates the operation of the cooling system with an increased steam velocity obtained by the use of a Venturi jet circulator through which the steam passes from the engine water jacket 16 to condenser tank 24. The Venturi passage in the form of an injector or jet pump may be formed separately and used in lieu of duct 20 or the Venturi passage may be provided by a Venturi insert which is utilized in conjunction with duct 20 as shown in Figure 1. A Venturi insert illustrated in Figure 2 of the drawings has been found to be very efficient in my improved cooling system, and as is indicated in the drawing, the insert is formed to be positioned and secured within the duct through which steam is discharged from the engine cylinder water jacket.

The improved insert formed with a Venturi passage therethrough comprises an annular member 70 which is adapted to be secured within duct 20 and extends between the inlet and outlet thereof. Annular bosses or extensions 71 provided adjacent to the inlet and outlet of the insert engage the wall of duct 20 to maintain the insert in place. Annular member 70 is provided with a series of apertures 72 which extend around the wall of the member adjacent to the inlet side thereof when the member is positioned within duct 20. The wall of annular member 70 diverges in the direction of the stream flow and the most restricted portion of the passage is provided in the area wherein apertures 72 are located. A flared entrant portion is provided between the terminal end of the Venturi insert and the restricted portion wherein the apertures 72 are positioned. The walls of duct 20, annular bosses 71 and the wall of the insert form an annular chamber or passage between apertures 72 and orifice 22 through which coolant flows. The annular member is secured within duct 20 by the use of pins 74 or other suitable fastening devices which extend through the member into the wall of the duct.

When the annular member is inserted within duct 20, a flow path exists between inlet orifice 22 and apertures 72 whereby coolant flowing through orifice 22 will pass through the orifices

72 into the flow stream passing through the annular member. The placement of the annular member 70 within duct 20 creates a Venturi flow passage for steam being discharged from the engine cylinder jacket and the steam jet passing the restricted area wherein apertures 72 are positioned creates a region of negative pressure which aids the introduction of condensate flowing in pipe 46 through orifices 22 and 72 into the stream of steam wherein it intermingles with the steam. The steam is thus condensed during which it gives up heat whereby the temperature of the condensate is elevated. The coolant after the temperature thereof has been increased flows through the cooling path in the manner aforescribed. The impact of the intermixed steam and condensate in inlet 56 of ram tube 52 causes a portion of the coolant to be directed through feed line 50 to the bottom portion of the engine cylinder jacket in the manner which has previously been discussed. It will be apparent that the use of the Venturi insert within duct 20 serves to provide a region of increased velocity and reduced pressure over the velocities and pressures achieved in the duct disclosed in Figure 1.

It will be understood that the relative cross sectional dimensions of duct 20, opening 56 of ram tube 52, feed line 50, and orifice 22, as well as those of the associated passages of the flow path will be selected in accordance with the cooling requirements of the engine. Under normal full load operating conditions of the engine, coolant is transferred to the engine cylinder water jacket at a flow rate to insure operation under steaming conditions.

The cooling system of the present invention serves to maintain a substantially constant temperature of the engine cylinders during operation of the engine. Further, the coolant is circulated through both the engine jacket and through the heat exchange devices without the use of valves, pumps, or other accessories having moving parts. As has heretofore been discussed, the amount of water circulated through the engine jacket is dependent upon the velocity of the steam flowing in duct 20 or through the Venturi orifice, and this velocity is in turn dependent upon the operating temperatures of the engine. Thus, the flow of coolant through the engine jacket is a function of the output or load of the engine. The improved coolant circulatory system has the further advantage that the cooling capacity of the volume of water in the radiator is sufficient to continue the jet condensing and circulating action for a period of time after the engine has ceased operation. This continued flow of coolant serves to absorb the residual heat of the engine cylinders and to dissipate it in the heat exchange device, thereby eliminating the blowing off of steam and the loss of coolant from the system.

I claim:

1. In a coolant circulatory system for a combustion engine provided with a water jacket within which steam is generated during operation of said engine, the combination comprising a discharge duct leading from said water jacket through which steam flows in a stream at high velocity and at a pressure below the average ambient pressure of the system, orifice means in said discharge duct through which a liquid coolant is introduced into said duct to intermix with said steam in the flow stream, and a feed line communicating between the high velocity region of the flow stream within said discharge duct and said water jacket through which coolant is de-

livered to said jacket by the impact force of the flow stream.

2. In a coolant circulatory system for an internal combustion engine provided with a water jacket within which steam is generated during the operation of said engine, the combination comprising a duct connected to said water jacket through which steam generated in said jacket flows at a high velocity and at a pressure below the average pressure of the system, an orifice positioned in said duct, a heat exchange device having the intake thereof connected to receive the discharge of said duct, conduit means connecting the outlet of said device to said orifice whereby steam flowing through said heat exchange device is cooled and the liquid coolant is returned to the reduced pressure region in said duct to intermix with steam issuing from said water jacket, and a feed line having the intake thereof positioned within the duct to receive the impact of high velocity flow of said intermixed steam and condensate and the outlet thereof connected to said water jacket.

3. In a coolant circulatory system for an internal combustion engine provided with a water jacket within which steam is generated during operation of said engine, the combination comprising a condenser tank provided with an inlet and outlet, a duct positioned between said inlet and said water jacket through which steam generated in said jacket flows at a high velocity and at a pressure below the average pressure of the system, an orifice positioned in said duct, a radiator having the upper portion thereof in communication with the outlet of said condenser tank and the lower portion thereof connected to said orifice whereby the coolant flowing through said radiator is introduced into said duct to intermix with the steam issuing from said water jacket, and means to convey coolant to said water jacket comprising a feed line having the intake thereof positioned within said duct to receive the impact of the high velocity flow stream of said intermixed steam and liquid coolant and the outlet thereof connected to said water jacket.

4. In a coolant circulatory system for an internal combustion engine provided with a water jacket within which steam is generated during operation of said engine, the combination comprising a condenser tank provided with an outlet positioned above the normal cold water level in the system, a duct positioned below the normal cold water level of the system connecting said water jacket and condenser tank, an orifice in said duct, a radiator having a vapor connection between an upper header thereof and the outlet of said condenser tank and a lower header connected by a condensate return line to said orifice, a feed line discharging into said water jacket having the intake thereof positioned within said duct and directed toward the water jacket connection, and means for maintaining the pressure in the system above atmospheric pressure during circulation of the coolant through said radiator and said feed line.

5. In a coolant circulatory system for an internal combustion engine provided with a water jacket within which steam is generated during the operation of the engine, the combination comprising, a Venturi jet circulator having the intake thereof connected to receive the steam issuing from said water jacket, a flow passage from the output of said jet circulator to the reduced pressure region of said jet comprising a

heat exchange device wherein the coolant is cooled and returned to the jet circulator to intermix with the steam issuing from said jacket, and a feed line connected to supply coolant to said water jacket having the intake thereof positioned in the outlet of the Venturi jet whereby coolant is delivered to the water jacket by the impact force of the jet stream.

6. In a coolant circulatory system for an internal combustion engine provided with a water jacket within which steam is generated during the operation of the engine, the combination comprising a Venturi jet circulator having the intake thereof connected to receive the steam issuing from said water jacket, a flow passage from the output of said jet circulator to the reduced pressure region of said jet comprising a heat exchange device wherein the coolant is cooled and returned to the jet circulator to intermix with the steam issuing from said jacket, a feed line connected to supply coolant to said water jacket having the intake thereof positioned in the outlet of the Venturi jet whereby coolant is delivered to the water jacket by the impact force of the jet stream, and venting means for said system comprising a spring biased valve for maintaining the pressure in the system above atmospheric pressure during operation of the engine.

7. In a coolant circulatory system for an internal combustion engine provided with a water jacket within which steam is generated during operation of said engine, the combination comprising a condenser tank provided with an inlet and an outlet, a Venturi jet circulator having the intake thereof connected to receive steam issuing from said water jacket and the outlet thereof connected to said condenser tank inlet, a radiator having the upper portion thereof in communication with the outlet of said condenser tank and the lower portion thereof connected with the reduced pressure region of said jet whereby coolant cooled in said radiator is fed to and intermixed with steam issuing from said water jacket, and means to convey coolant to said water jacket comprising a feed line having the intake thereof positioned in the outlet of the Venturi jet whereby coolant is delivered to the water jacket by the impact force of the jet stream.

8. In a coolant circulatory system for an internal combustion engine provided with a water jacket within which steam is generated during operation of said engine, the combination comprising a condenser tank provided with an outlet positioned above the normal cold water level in the system, a Venturi jet circulator positioned below the normal cold water level of the coolant and connected between the outlet of said water jacket and the inlet of said condenser tank, a radiator having a vapor connection between an upper header thereof and the outlet of said condenser tank and a lower header connected by a condensate return line to the low pressure region of said Venturi jet circulator, and a conduit having the outlet thereof connected to the water jacket and the inlet thereof located below the normal cold water level of the system and positioned in the outlet of the Venturi jet circulator.

9. In a coolant circulatory system for an internal combustion engine provided with a water jacket within which steam is generated during operation of said engine, the combination comprising a condenser tank provided with an outlet positioned above the normal cold water level of the system, a Venturi jet circulator positioned

below the normal cold water level of the coolant and connected between the outlet of said water jacket and the inlet of said condenser tank, a radiator having a vapor connection between one header thereof and the outlet of said condenser tank and another header connected by a condensate return line to the low pressure region of said Venturi jet circulator, a feed line having the outlet thereof connected to the water jacket and the inlet thereof located below the normal cold water level of the system and positioned in the path of the Venturi jet adjacent to the outlet thereof, and venting means positioned in said feed line to permit the escape of entrapped gas.

10. In a coolant circulatory system for an internal combustion engine provided with a water jacket within which steam is generated during the operation of said engine, the combination comprising a duct connected to said water jacket through which steam generated in said jacket flows at a high velocity and at a pressure below the average ambient pressure of the system, an orifice positioned in said duct, a heat exchange device having the intake thereof connected to receive the discharge of said duct, conduit means connecting the outlet of said device to said orifice whereby coolant flowing through said heat exchange device is cooled and returned to the reduced pressure region in said duct to intermix with steam issuing from said water jacket, a feed line having the intake thereof positioned within the duct to receive the impact of the high velocity flow path of said intermixed steam and condensate and the outlet thereof connected to said water jacket, and venting means positioned in said feed line to permit the escape of entrapped gas.

11. In a coolant circulatory system for an internal combustion engine provided with a water jacket within which steam is generated during operation of the engine, the combination comprising a condenser tank provided with an inlet and an outlet, a tubular duct having the inlet thereto connected to said water jacket and positioned to discharge the steam generated in said jacket to the inlet of said condenser tank, an orifice positioned in the wall of said duct, an annular member positioned within said duct provided with apertures located in the wall of said member adjacent to one end thereof and having

50

a diverging passage extending from said apertures to the mouth of the member with a fluid path extending from said orifice to said apertures, a radiator having the upper portion thereof in communication with the outlet of said condenser tank and the lower portion thereof connected to said orifice, and a feed line discharging into said water jacket having the intake thereof positioned within the mouth of said annular member and directed toward the inlet of said duct.

12. In a coolant circulatory system for an internal combustion engine provided with a water jacket within which steam is generated during operation of the engine, the combination comprising a condenser tank provided with an inlet and an outlet, a tubular duct having the inlet thereto connected to said water jacket and positioned to discharge the steam generated in said jacket to the inlet of said condenser tank, an orifice positioned in the wall of said duct, an annular member positioned within said duct provided with apertures located in the wall of said member adjacent to one thereof and having a diverging passage extending from said apertures to the mouth of the member with a fluid path extending from said orifice to said apertures, a radiator having the upper portion thereof in communication with the outlet of said condenser tank and the lower portion thereof connected to said orifice, a feed line discharging into said water jacket having the intake thereof positioned within the mouth of said annular member and directed toward the inlet of said duct, and venting means for said feed line positioned to discharge entrapped gas into said condenser.
